UNITED STATES PATENT OFFICE.

WILLIAM M. SHEEHAN, OF ST. LOUIS, MISSOURI, AND EINAR G. HALLQUIST, OF EDWARDSVILLE, ILLINOIS, ASSIGNORS TO COMMONWEALTH STEEL COMPANY, OF GRANITE CITY, ILLINOIS, A CORPORATION OF NEW JERSEY.

ROCKER CENTERING DEVICE.

Application filed November 2, 1927. Serial No. 230,504.

Our invention relates to railway rolling stock and consists in a novel rocker structure for use in centering devices such as are utilized for mounting a bolster, or other transversely moving part, on the frame of a truck. The device may be used on a two or four wheel trailer truck or on a pony truck and the general operation of such centering device is clearly disclosed in Woodward Patent No. 1,060,222.

Our present invention consists in providing rockers for devices of this type with renewable bearings of the type illustrated and described herein, which bearings may be of a restricted area and applied to the body of the rocker and adapted to prolong the useful life of the rocker. When worn to an appreciable extent the bearing elements may be replaced with other similar bearing elements without renewing the body of the rocker.

In the accompanying drawings which illustrate our invention—

Figure 1 is a one-half transverse vertical section through a pony truck equipped with a rocker centering device utilizing one of our rockers and is taken approximately on line 1—1 of Figure 2.

Figure 2 is a longitudinal vertical section through the same truck and is taken approximately on line 2—2 of Figure 1.

Figure 3 is an enlarged detail elevation of a modified form of rocker.

Figure 4 is a similar view of another modified form of rocker.

In the construction illustrated in Figures 1 and 2, the truck is shown with the usual wheels 1, axles 2, and truck frame 3 including transom members 4 having a bottom connecting web 5 which mounts rocker seats 6.

All of the above parts are of well known construction and do not form any part of our present invention.

Each of the rocker members mounted on seats 6 comprises interconnected spaced rocker body portions 7 generally triangular in shape and each provided on its base with spaced elements 8 which are seated in recesses in the bottom of the rocker and project therefrom to form semi-cylindrical journal elements. Preferably these elements may take the form of hard steel rollers which are seated in the recesses in the bottom of the body of the rocker. They may be welded to the rocker at intervals as indicated at W and may be

removed and replaced when desired without scrapping the body of the rocker. Naturally the life of the rocker will be much longer than the usual cast rocker with integral journal portions as has been used previously.

Similarly the apex of the rocker which carries the bolster 9 may be provided with a separate insert 10 which may be welded to the body of the rocker and removed and replaced when worn.

Another form of the journal portion of the rocker is illustrated in Figure 3 in which the entire base 11 of the rocker is formed of a separate member and attached to the rocker body 12 by welding or other suitable means. In this modification we indicate tongues 13 on the journal portion fitted into recesses in the body portion.

Another modification is indicated in Figure 4 in which the body portion 14 of the rocker is provided with integral semi-cylindrical projections 15, each of which has applied thereto a semi-cylindrical convex wear plate 16 attached to the body by welding as indicated at W.

It will be obvious that with the above construction the body of the rocker will last indefinitely, barring accidents, and the replacement of rockers because of wear, as is now practiced, may be eliminated.

While we have referred to the use of bearing elements of different material than the body of the rocker, and preferably of harder material, we consider the use of separable bearing elements of the same material as a novel construction and contemplate the exclusive use of such structure as well as any other modification of our preferred structure as come within the scope of our claims.

We claim:

1. A railway centering device rocker comprising a body portion and an element of different material projecting from said body portion and forming a replaceable semi-cylindrical journal.

2. A railway centering device rocker comprising a body portion of cast metal and an element of harder metal projecting from said body portion and forming a replaceable semi-cylindrical journal.

3. In a railway centering device rocker, a body portion, and a journal forming member, having a downwardly facing convex surface, detachably secured to said body portion.

4. In a railway centering device rocker, a body with a recess in its lower face and a cylindrical member of different material seated in said recess and forming a journal element projecting therefrom. 30
5. In a railway centering device rocker, a cast metal body and a separately formed roller attached to the bottom of said body and forming a journal element therefor. 35
- 10 6. In a railway centering device rocker, a cast metal body with transverse recesses in its lower face, and rollers of hard steel seated in said recesses and projecting therefrom to form spaced journal elements for the rocker. 40
- 15 7. A railway centering device rocker provided with hard steel bearing elements at its supported and supporting points. 45
8. A railway centering device rocker provided with renewable hard steel bearing elements at its supported and supporting points. 50
9. A railway centering device rocker comprising a triangular-shaped body portion of cast metal, spaced journals extending transversely of the base of said body portion, and a bearing element at the apex of said body portion, said journals and element being formed of hard steel metal and detachable from said body portion for renewal purposes. 55
- 25 10. A railway centering device rocker com-
prising a triangular shaped body portion, 30
spaced journal elements extending trans-
versely of the base of said body portion, and a
bearing element at the apex of said body portion,
said elements being detachable from
said body portion for renewal purposes. 35
11. A railway centering device rocker com-
prising a body portion and a separable ele-
ment projecting from said body portion and
forming a replaceable semi-cylindrical
journal. 40
12. In a railway centering device rocker, a
body portion with recesses in its lower face,
and separately formed rollers seated in said
recesses and projecting therefrom to form
spaced journal elements for the rocker. 45
13. In a railway centering device rocker, a
body portion with a recess in its lower face,
and a removable element seated in said recess
and projecting therefrom to form a cylin-
drical journal element for the rocker. 50
14. A railway centering device rocker pro-
vided with separable bearing elements at its
supported and supporting points. 55

In testimony whereof we hereunto affix our
signatures this 22d day of Oct., 1927.

WILLIAM M. SHEEHAN.
EINAR G. HALLQUIST.
